UNITED STATES PATENT OFFICE.

JULIUS GALL, OF ABLEMAN, WISCONSIN.

HANGING CABINET.

957,324.

Specification of Letters Patent. Patented May 10, 1910.

Application filed January 20, 1910. Serial No. 529,015.

To all whom it may concern:

Be it known that I, JULIUS GALL, a citizen of the United States, residing at Ableman, in the county of Sauk and State of Wisconsin, have invented new and useful Improvements in Hanging Cabinets, of which the following is a specification.

My invention relates to hanging cabinets; and it has for its object to provide a hanging cabinet embodying such a construction that thin and inexpensive material may be utilized in the manufacture of its hangers, in such manner that the hangers are possessed of the requisite stiffness and strength, and the lower sections of the hangers are adjustable as to height on the upper sections thereof.

Other advantageous characteristics of the invention will be fully understood from the following description and claim when the same are read in connection with the drawings, accompanying and forming part of this specification, in which:

Figure 1 is a perspective view of my improved cabinet in proper position for use. Fig. 2 is a vertical section of the same. Fig. 3 is a detail rear elevation of one of the hangers. Fig. 4 is an enlarged detail horizontal section, taken in the plane indicated by the line 4—4 of Fig. 3, looking downward.

Similar letters designate corresponding parts in all of the views of the drawings, referring to which:

A is an apartment wall, and B, a piece of molding thereon.

C C are the hangers of my improved hanging cabinet. Inasmuch as the said hangers are identical in construction a detailed description of the one shown in Figs. 2 to 4 will impart a definite understanding of both. The hanger referred to comprises an upper section *a* and a lower section *b*. The upper section *a* comprises a major vertical portion and a hook *c* at the upper end thereof, adapted to engage the piece of molding; and it is formed of a single piece of thin sheet-metal and in the manner best shown in Figs. 3 and 4—*i. e.*, it has a front thickness *d* which extends throughout its width, and reinforcing and stiffening flanges *e* bent tight against the back of the thickness *d*. The lower section *b* of the hanger comprises a vertical portion *f*, a horizontal arm *g* that reaches forward from the lower end of said vertical portion, and an oblique

portion *h* which serves in combination with the portions *f* and *g* to form a shelf-supporting stirrup. The vertical portion *f* of section *b* is formed of thin sheet-metal, and comprises a thickness *i* which extends throughout the width of the portion, and rearwardly and inwardly bent flanges *j*, which are designed to straddle the vertical portion of the upper section *a* so as to hold the sections together and permit of the lower section being moved up and down on the upper section as occasion demands. The horizontal arm *g* is a continuation of the thickness *i* of the vertical portion *f*, and said horizontal portion *g* corresponds in thickness to the inclined portion *h* which is connected, adjacent its upper end, to the thickness *i* of the vertical portion *f* through the medium of a set screw *D*, which set screw extends through and bears in the portion *h* and the thickness *i* and is designed to serve the additional purpose of engaging the vertical portion of the section *a* so as to adjustably fix the section *b* thereto. From this it follows that the section *b* may be adjustably positioned at various distances from the piece of molding *B*, according to the height at which it is desired to dispose the shelf *E*, which may be of wood, metal or any other material, and is connected with the horizontal arms *g* of the lower hanger sections *b* by bolts *k*, as shown. I prefer to connect the shelf *E* to the arms *g* as stated, but do not desire to be understood as limiting myself to the said connection, inasmuch as when desired the shelf may be simply placed on the arms *g*.

I employ a back *F* for holding the hangers *C* together and against swinging movement independently of each other, and I also utilize the said back as a stop for books or other articles placed on the shelf. I prefer to employ the construction illustrated in the back—*i. e.*, to have the back comprise upper and lower bars *l* and *m*, connected at *p* to the front thicknesses *i* of the portions *f*, and bars *r* extending between and connecting the bars *l* and *m* together at intervals in the length thereof.

By reason of the manner in which the sections *a* and *b* are constructed, it will be observed that they are possessed of great stiffness and strength, notwithstanding the thinness of the sheet-metal utilized; and it will also be observed that while the sections *b* are adapted to be readily adjusted up and

down on the sections *a* to position the shelf at the proper height and to be as readily fixed with respect to the sections *a*, there is no liability of either section *b* being permitted to casually move downward under the weight imposed on the shelf *E*.

In addition to the practical advantages ascribed to the improved hanging cabinet, it will be appreciated that while the construction of the cabinet is simple and inexpensive, it is calculated to enhance rather than detract from the finished appearance of an apartment.

Having described my invention, what I claim and desire to secure by Letters-Patent, is:

In a hanging cabinet, the combination of hangers spaced apart and respectively comprising an upper section of thin sheet-metal having its upper portion bent into a hook; a lower section having a vertical portion comprising a front thickness and flanges thereon straddling the vertical edges of the

upper section, an integral arm bent forwardly from the lower end of the said front thickness, an integral inclined portion bent upwardly from said arm and extending between the same and the vertical portion, and a set screw bearing in said inclined portion and the front thickness of the vertical portion and engaged with the upper section to serve the two-fold function of connecting said portion and adjustably fixing the lower section on the upper section; a back extending between and connected to the vertical portions of the lower sections; and a shelf carried on the arms of the said lower sections.

In testimony whereof I have hereunto set my hand in presence of two subscribing witnesses.

JULIUS GALL.
